UNITED STATES PATENT OFFICE.

HARRY SCHREIBMAN AND LOUIS GOLDBERG, OF BROOKLYN, NEW YORK.

DESIGN FOR A LIGHTING FIXTURE.

Application filed November 15, 1928. Serial No. 28,905. Term of patent 3½ years.

To all whom it may concern:

Be it known that HARRY SCHREIBMAN and LOUIS GOLDBERG, citizens of the United States, and residents of the city of New York, borough of Brooklyn, in the county of Kings and State of New York, have invented a new, original, and ornamental Design for a Lighting Fixture, of which the following is a specification, reference being had to the accompany-

ing drawing, forming part thereof, in which, the figure is a perspective view of a lighting fixture embodying the invention.

We claim:

The ornamental design for a lighting fixture, as shown.

Dated, New York city, Nov. 10, 1928.

HARRY SCHREIBMAN.
LOUIS GOLDBERG.
